[57] CLAIM

The ornamental design for a microscope support and stage design, as shown and described.

DESCRIPTION

FIG. 1 is a front perspective view of a microscope support and stage showing my new design;

FIG. 2 is a front view of the design of the microscope support and stage of FIG. 1;

FIG. 3 is the rear view of the design of the microscope support and stage of FIG. 1;

FIG. 4 is a side view of the design of the microscope support and stage of FIG. 1;

FIG. 5 is the opposite side view of the design of the microscope support and stage of FIG. 1; and,

FIG. 6 is a top view of the design of the microscope support and stage of FIG. 1.

In the FIGURES, broken lines are not part of the claimed design.
